UNITED STATES PATENT OFFICE

2,266,195

TOOTHBRUSH

Robert Lay Hallock, Newburgh, Ind.

Application December 13, 1938, Serial No. 245,345

1 Claim. (Cl. 15—167)

My invention relates to tooth brushes and has for its object to provide a tooth brush better adapted to conform to tooth set contours. In accordance with the invention, bristle carrying sections are mounted to have relative movement, preferably by independent cantilever support.

The preferred form of my invention is shown in the accompanying drawing, forming a part of this specification, and of which:

Fig. 1 is a top plan view;

Fig. 2 is a side view, partly in section, on the line 2—2 of Fig. 1;

Fig. 3 is taken on line 3—3 of Fig. 1;

Fig. 4 is taken on line 4—4 of Fig. 1; and

Figs. 5 and 6 show the action of the brush 15 in use.

The toothbrush includes a handle 10. Extending forwardly from the handle 10 are two lateral fingers 11 and an intermediate or central finger 12. At the forward end of the central finger 12 is a bristle carrying section 13 in which are mounted a group of tufts of bristles 14. Central finger 12 may be said to be an arm or extension carrying the bristle section 13, 14 as an independent unit. At the forward end of lateral fingers or arms 11 are bristle carrying sections 15 in each of which are mounted bristle tufts 16. Tufts 16 are behind and in longitudinal alignment with certain of the tufts 14. Lateral connecting pieces 17 connect bristle sections 15 with a front or leading bristle carrying section 18 in which are mounted a group of tufts of bristles 19. Bristles 19 are in alignment with bristles 14. Lateral fingers 11 carry bristle sections 15 and 18 independently of bristles 14.

For the purpose of description, it may be considered that the parts 10, 11, 17 and 18 constitute a tooth brush having a central portion removed forming a through-aperture in which is mounted a small tooth brush made up of the bristle carrying section 13 and its handle or arm 12, the end of arm 12 being joined to the main handle 10. Except for the attachment of arm 12 to handle 10, parts 12 and 13 are entirely independent of the remaining parts. There is, in effect, a narrow groove around parts 12 and 13 except at the rear point of attachment which passes through the body of the brush whereby the independently mounted tufts can have independent movement in the general line of extent of the bristles.

The handle 10, fingers 12 and 11, connecting pieces 17 and bristle carrying sections (not including the bristles) are preferably made integral and of an elastic resilient material of such character that the handle 10 is essentially rigid while the fingers 11 and 12 are quite flexible.

Such materials are known and are at present used for tooth brushes. Various molded plastics may be used of either the field of resin derivatives or cellulose derivatives. Examples of such substances are phenol-formaldehyde resins and pyroxylin. In order to increase the yieldability of the fingers 11 and 12 they may be made of reduced cross-section as shown at 20.

It may be said that the bristle groups 14 on 10 the one hand and the bristle groups 16 and 19 on the other hand are independently carried at the ends of the respective cantilevers 12 and 11.

The action produced by the independent support of the longitudinally displaced bristle tufts is illustrated in Figs. 5 and 6. The tufts can accommodate themselves to teeth which have a generally convex or concave curvature as a group. Considering spaced teeth as in a given plane, the tufts 14 can be moved into contact with an intermediate tooth to one side or the other by slight hand pressure on the handle as is ordinarily applied.

In manufacture, the body may be molded directly in the form shown, or it may be molded 25 as a solid block and the slot between the parts may be sawed out.

It will be seen that in the construction as disclosed the bristles are relatively movable to conform to concave and convex contours while 30 appreciable relative sideways movement of bristle groups is prevented.

It will be understood that the invention is not limited to the preferred form disclosed.

What I claim is:

35 A tooth brush including a main bristle unit, a handle, a connection between said handle and said main unit, said main unit including longitudinally spaced bristle carrying sections having bristle groups in longitudinal alignment, a central bristle carrying section disposed between the bristle carrying sections of said main unit and carrying a plurality of groups of bristles in longitudinal alignment and between bristle groups of said main unit, said main unit having parts 40 extending laterally on both sides of said central bristle carrying section and close thereto, a member connecting said central bristle carrying section with said handle, said member being resilient relative to the connection between the handle and the main unit to permit movement of the bristles of the central section relative to those of the main unit in the general direction of the bristles so that the bristles in their entirety can conform to concave and convex contours, while appreciable relative sideways movement of the bristle groups is prevented.

ROBERT LAY HALLOCK.
